WATER HEATER CONTROL SYSTEM

Clark M. Osterheld, Stoughton, Wis., assignor to
 McGraw Electric Company, Elgin, Ill., a corpora-
 tion of Delaware

Application January 1, 1944, Serial No. 516,693

13 Claims.

(Cl. 219—39)

My invention relates to water heaters and particularly to control systems for tank water heaters.

An object of my invention is to limit the maximum energy input into a tank.

Another object of my invention is to provide a control system for a water heater to effect selective energization of a plurality of heaters under predetermined conditions of demand for hot water.

Another object of my invention is to provide a single heater control switch mountable on a tank and controlled jointly and simultaneously by temperature conditions of water throughout the tank.

Other objects of my invention will either be apparent from a description of a control system embodying my invention or will be set forth in the course of such description and pointed out particularly in the appended claims.

In the drawings,

Figure 1 is a vertical section of a water tank showing the electric circuits and contacts when the water in the top and bottom of the tank is cold.

Fig. 2 is a fragmentary sectional view taken on the line 2—2 of Fig. 1.

Fig. 3 is a fragmentary view showing the position of the contacts when the water in the upper part of the tank is hot.

Fig. 4 is a fragmentary view showing the position of the contacts when all of the water in the tank is hot.

Fig. 5 is a top plan view of the parts shown in Fig. 7.

Fig. 6 is a fragmentary end view of the parts shown in Fig. 7.

Fig. 7 is a side elevational view of a plural-position plural-contact heater-control switch.

Fig. 8 is a fragmentary sectional view similar to that of Fig. 1 showing a modified form of device embodying my invention, and,

Fig. 9 is an enlarged view of a portion of Fig. 8.

The control system and method of control embodying my invention applies more particularly to domestic hot water tanks having an upper and a lower heater therefor, the main object of my invention being to so control the heaters that there shall always be at least a small quantity of hot water available for immediate use and that the maximum energy input to heat the water shall be definitely fixed.

I have shown a hot water tank 11 surrounded by heat insulation 13 and an outer casing 15 therearound all in a manner well known in the art. The tank is provided with a lower cold water

inlet pipe 17 and an upper hot water outlet pipe 19 and I may provide also supports 23 all of which are now well known in the art.

I provide an upper electric heater 25 and a lower electric heater 27 each of which may be positioned around the tank and located in a tunnel 29.

Referring first to Figs. 1 to 7 inclusive I have there shown a plural-contact plural-position heater control switch 31 adapted to be actuated by an upper thermally-expansible rod 33 and a lower thermally-expansible rod 35. The upper rod 33 has its upper end suitably fixedly secured as by a bracket 37 to the upper end of the tank 11 while the lower rod 35 has its lower end fixedly secured to a bracket 39 which in turn is fixedly secured against the lower end portion of the tank 11. The brackets 37 and 39 are of high-heat conducting material and are secured in good heat-receiving relation to the tank. The heat-insulating material 13 is provided with an elongated recess 41 for locating the two substantially coaxially aligned rods 33 and 35 which as will be noted from Fig. 1 of the drawings are so mounted as to extend longitudinally of the tank 11 and spaced therefrom. I may provide plates 43 of any suitable material spaced apart so as to prevent convection currents of air occurring in the elongated recess 41. The two rods 33 and 35 are made of a high expansion material such as aluminum. The linear temperature co-efficient of expansion of aluminum is substantially twice that of the iron or steel of which the usual domestic hot water tank is made.

The plural-contact plural-position switch 31 is supported on the upper end of lower rod 35 as by a vertically-extending end portion 44 of a frame member 45 of the switch by machine screws 46. Portion 44 includes a pair of upwardly-extending lugs 47 having a pivot pin 49 adjacent its upper end to receive an actuated arm 51 which may be of substantially L-shape and be pivotally supported on pivot pin 49 in lugs 47. An adjusting screw 53 having a lock nut 55 thereon extends through the horizontal portion of arm 51 and is adapted to engage against the lower surface of upper rod 33.

Frame 45 comprises a vertically upwardly-extending portion 57 having a pair of lugs 59 extending therefrom toward the tank and an arm 61 is supported on lugs 59 as by a pivot pin 63. The lower end of arm 61 is pivotally connected with a horizontal arm 65 the right hand end portion of which is adapted to move horizontally in a pair of supporting and guiding stirrups 67 and

68 which are connected to or a part of a pair of spaced horizontal portions 69 of frame 45. The upper end of arm 51 is rounded and adapted to engage a plane contact surface of arm 61 adjacent its upper pivoted end, the design, construction and adjustment of arms 51, 61 and 65 being such that small changes in the distance between the end surfaces of rods 33 and 35 will cause appreciable movements of arm 65.

The upper end portion of member 51 has secured thereon a pair of contacts 71, a block 73 of electric-insulating material being provided to suitably insulate them from frame 45. A first two-part arm 75 is pivotally supported at its lower end adjacent the inner end of parts 69 and has insulatedly mounted thereon at its upper end a contact bridging member 77. An over center spring 79 has its upper end connected to a pivot pin on arm 75, the lower end of spring 79 being suitably secured to a vertically upwardly-extending lug 81 on arm 65.

A second swinging arm 83 is pivotally mounted adjacent the outer end portion of member 69 and has insulatedly mounted thereon at its upper end a pair of contact members 85, of L-shape. An over center spring 87 has its upper end pivotally connected to the upper end portion of arm 83 while its lower end is connected to a lug 89 constituting a part of or secured to arm 65.

A stop member for the two arms 75 and 83 includes a horizontally-extending member 91 having an inner stop lug 93 and an outer stop lug 95 thereon adapted to be engaged by the arms 75 and 83. Reference to Fig. 7 will show that the center line of coil spring 79 is closer to the pivot point of arm 75 than is the center line of spring 87 from the pivot point of arm 83. This has the result that arm 75 will be caused to move over against stop lug 93 with a snap action upon movement of arm 65 in a right hand direction, without affecting the second arm 83. Further movement of arm 65 in a right hand direction will cause turning movement of the second arm 83 with a snap action against stop lug 95. Upon movement of arm 65 in a left hand direction, arm 83 will be caused to move first with arm 75 moving upon further movement of arm 65 in a left hand direction. Turning movement of arm 75 in a clockwise direction will cause deenergization of the upper heater 25 and energization of the lower heater 27 and turning movement of arm 83 in a clockwise direction will cause deenergization of the lower heater 27.

The arm 65 which is adapted to be moved in a straight line axially thereof is biased into its left hand limiting position by a spring 97, and a pair of rollers 98 are provided in portion 69 to permit of easy movement of bar 65.

I provide a bracket 99 which may be secured against the outside of the tank by screws 101 extending into metallic blocks 103, heat-insulating material 105 being provided therebetween to suitably heat-insulate the bracket 99 from the temperature of the tank water. The bracket is provided with lateral extensions 107 at its upper and lower ends, having apertures therein to receive the rods 33 and 35 to maintain them in alignment, it being understood that the rods may move longitudinally in the portions 107.

Let it be assumed that the tank has been filled with cold water, in which case the longitudinal dimension of the tank will be a minimum relative to its dimension afterwards when substantially all of the water in the tank has been heated to a predetermined temperature. Where I

have used the words "hot water" hereinafter I refer to water which may have a temperature on the order of say 150° F. For simplicity it may be assumed that the temperature of the cold water is the usual normal room temperature, namely 70° F. The length of the rods 33 and 35 will also be a minimum since they also will have a temperature of substantially 70° F. Under these conditions the design, construction and ad-

justment of the expansion rods 33 and 35 and of the plural-contact plural-position heater control switch 31 is such that the parts thereof will be in the positions shown particularly in Fig. 7 of the drawings, from which it will be noted that the contact bridging member 77 is in engagement with the contacts 71 so that the upper heater 25 alone is energized. This will result in heating up of a relatively small amount of water in the top portion of the tank with the result that the temperature of the bracket 37 will be raised from substantially 70° F. to substantially 150° F. with the result that the upper expansion rod 33 will have its length increased a greater amount than will occur in the length of the upper portion of the tank with the result that the lower end portion of rod 33 will cause downward movement of adjusting screw 53 with an attendant turning movement of arm 51 in a clockwise direction. This will result in pressure against arm 61 to counteract the tendency of spring 97, with resultant turning movement of arm 61 in a counter-clockwise direction and attendant movement of arm 65 toward the right, as seen in Fig. 7. It will be noted that the position of springs 79 and 87 are relatively different so that the right hand movement of arm 65 will cause swing movement of arm 75 in a clockwise direction before swing movement of arm 83 will occur. This will cause engagement of contact bridging member 77 with the two contact terminals 85 with the result that the upper heater 25 is deenergized but the lower heater 27 is energized. The diagram of connections is shown in Fig. 1, which shows two supply circuit conductors 109 and 111.

Heating of the rest of the water in the tank 11 will continue until substantially all of the water in the tank is hot. When this occurs the temperature of bracket 39 will also be on the order of substantially 150° F. with the result that the temperature of the lower expansion rod 35 will also be on the order of 150° F. with consequent increase in length of expansion rod 35.

The result of this expansion of rod 35 is that arm 51 is caused to turn in a clockwise direction still further with resultant turning movement of arm 61 in a counter-clockwise direction and further right hand movement of arm 65. When arm 65 has been moved against spring 97 sufficiently so that the lower end of spring 87 has been moved beyond the pivot point of arm 83, the arm 83 will turn in a clockwise direction against stop 95 so that the lower heater 27 is deenergized by reason of the disengagement of contact terminals 85 from contact bridging member 77.

It is thus evident that the single plural-contact plural-position switch is actuated jointly and simultaneously by the two expansion rods 33 and 35 which are subject to the thermal conditions of the water in the upper and in the lower parts of the tank so as to energize the upper heater only when all of the water in the tank is cold until such time as a part of the water in the upper portion of the tank has been heated after which the upper heater is deenergized and the

lower heater is energized until substantially all of the water in the tank is hot.

Referring now to Figs. 8 and 9 of the drawings I have there illustrated a modification of the control system shown in Figs. 1 to 7 and embodying my invention and have shown an upper rod 113 and a lower rod 115 secured fixedly respectively at the upper end of the upper rod against the upper end portion of the tank as by a bracket 117 and the lower end of the lower rod as by a bracket 119. Rods 113 and 115 are of non-expansive material or alloy such as Invar. The switch 31 is secured to the upper end portion of rod 115 as by a member 44 and an L-shaped lever arm 121 is pivotally mounted intermediate the horizontal part thereof on lugs 123. The lower face of the upper rod 113 has secured thereto a depending lug 125 having pivotal engagement with the left hand end portion of the horizontal arm of member 121. I provide a guide bracket 127, having perforated portions 129 at each end, to preserve the substantially co-axial alignment of rods 113 and 115, at least one of the rods, as for example 113, being movable in its guide 129. It will be evident from an inspection of Fig. 9 of the drawings that when the upper end portion of tank 11 has been expanded by being filled with hot water, with an increase in its longitudinal length, there will be a tendency for arm 121 to be turned in a clockwise direction with attendant movement of arm 61 in a counter-clockwise direction and movement of arm 65 toward the right. When arm 65 and particularly spring 79 have been moved sufficiently to the right so that the lower portion of spring 79 has been moved horizontally beyond the pivot point of arm 75, arm 75 will be moved in a clockwise direction, resulting in disengagement of bridging member 71 from contact terminal 71 with deenergization of the upper heater. Contact bridging member 71 has been moved into electrical engagement with contact terminals 85 on arm 83 so that lower heater 27 is now energized.

When substantially all of the water in the tank has been heated to say 150° F., the entire length of tank 11 is such that arm 121 will have been turned sufficiently in clockwise direction to cause further sliding movement of arm 65 toward the right so that arm 83 will have been turned in a clockwise direction against stop 95 with the result of disengagement of terminals 85 from bridging member 71 and resultant deenergization of the lower heater 27. The arm 75 is prevented from following the arm 83 by contacting the stop 93.

If it be assumed that hot water is demanded and a relatively small amount is used, say about one-third of a tank full, arm 65 will be caused to move toward the left sufficiently to cause swinging movement of arm 83 in a counter-clockwise direction to bring terminals 85 again in engagement with contact bridging member 71 whereby the lower heater 27 will again be energized, this energization continuing until substantially all of the water in the tank has again been heated to say 150° F. when bar 65 will be moved to the right to cause deenergization of the lower heater 27.

I am aware of other patents showing a very different control system for an upper and a lower tank heater comprising a control switch thermally actuated in accordance with the temperature of the water in the upper end portion of the tank and controlling not only the upper heater but also the lower heater. The lower heater is also pro-

vided with a thermally-actuable switch. In contradistinction to this system I may point out that my improved system includes a single plural-contact plural-position switch and two rod members, one of which supports the switch, the two rod members having their outer ends fixedly secured to end portions of the tank, the inner end portions of the rods extending substantially closely toward each other, relative movement of the ends of said rods occurring as a consequence of the different thermal linear expansion of the two rods and of the tank when the tank is filled with cold water or filled with hot water.

The device and system embodying my invention therefore provides a relatively simple control system and switch effective for the desired purpose of limiting the energy input into a tank and of always maintaining available for immediate use at least a predetermined amount of hot water.

Various modifications may be made in the device and system embodying my invention and all modifications thereof coming clearly within the scope of the appended claims are to be considered a part thereof.

25 I claim as my invention:

1. A water heater control system for a hot water tank having an upper and a lower electric heater for said tank, a single plural-contact plural-position switch for selectively controlling the energization of said heaters, an upper rod having its upper end secured fixedly to the upper end portion of said tank, a lower rod having its lower end secured fixedly to the lower end portion of said tank, said rods extending longitudinally of said tank with their inner ends spaced apart, and having different linear thermal expansion than said tank, means supporting said switch on the inner end of one of said rods and switch-actuating means engaged by the inner end of the other rod for causing movement of said switch into a position to effect deenergization of the lower heater and energization of said upper heater when the tank is substantially full of cold water.

45 2. A water heater control system for a hot water tank having an upper and a lower electric heater for said tank, a single plural-contact plural-position switch for selectively controlling the energization of said heaters, an upper rod having its upper end secured fixedly to the upper end portion of said tank, a lower rod having its lower end secured fixedly to the lower end portion of said tank, said rods extending longitudinally of said tank with their inner ends spaced apart, said rods having different linear thermal expansion than said tank, means supporting said switch on the inner end of one of said rods and switch-actuating means engaged by the inner end of the other rod for causing movement of said switch into a position to effect deenergization of the lower heater and energization of said upper heater when the tank is substantially full of cold water.

55 3. A water heater control system for a hot water tank having an upper and a lower electric heater for said tank, a single plural-contact plural-position switch for selectively controlling the energization of said heaters, an upper rod having its upper end secured fixedly to the upper end portion of said tank, a lower rod having its lower end secured fixedly to the lower end portion of said tank with their inner ends spaced apart, said rods having different linear thermal expansion than said tank, means supporting said switch on the inner end of one of said rods and switch-actuating means engaged by the inner end of the other rod for causing movement of said switch into a position to effect deenergization of the lower heater and energization of said upper heater when the tank contains a predetermined quantity of hot water in the upper portion thereof.

60 4. A water heater control system for a hot water tank having an upper and a lower electric heater for said tank, a single plural-contact plural-position switch for selectively controlling the energization of said heaters, an upper rod having its upper end secured fixedly to the upper end portion of said tank, a lower rod having its lower end secured fixedly to the lower end

portion of said tank, said rods extending longitudinally of said tank with their inner ends spaced apart and having different linear thermal expansion than said tank, means supporting said switch on the inner end of one of said rods and switch-actuating means engaged by the inner end of the other rod for causing movement of said switch into a position to effect deenergization of the lower heater and energization of said upper heater when the tank is substantially full of cold water and to effect deenergization of said upper heater and energization of said lower heater when the tank contains a predetermined quantity of hot water in the upper portion thereof and to effect deenergization of said lower heater when the tank is substantially full of hot water.

4. A water heater control system for a hot water tank having an upper and a lower electric heater therefor, a single plural-contact three-position switch for selectively controlling said heaters, a pair of rods having different linear thermal expansion than said tank, the length of each rod being slightly less than one-half of the length of the tank, extending longitudinally of the tank with the outer ends fixedly secured to the end portions of the tank, said rods jointly controlling said switch in accordance with the temperature of the water throughout the tank to cause energization of the upper heater only when the tank is full of cold water.

5. A water heater control system for a hot water tank having an upper and a lower electric heater therefor, a single plural-contact three-position switch for selectively controlling said heaters, a pair of rods having different linear thermal expansion than said tank, the length of each rod being slightly less than one-half of the length of the tank, extending longitudinally of the tank with the outer ends fixedly secured to the end portions of the tank, said rods jointly controlling said switch in accordance with the temperature of the water throughout the tank to cause energization of the upper heater only when the tank is full of cold water and to cause deenergization of the upper heater and energization of the lower heater when a predetermined part of the water in the tank has been heated to a predetermined temperature.

6. A water heater control system for a hot water tank having an upper and a lower electric heater therefor, a single plural-contact three-position switch for selectively controlling said heaters, a pair of rods having different linear thermal expansion than said tank, the length of each rod being slightly less than one-half of the length of the tank, extending longitudinally of the tank with the outer ends fixedly secured to the end portions of the tank, said rods jointly controlling said switch in accordance with the temperature of the water throughout the tank to cause energization of the upper heater only when the tank is full of cold water and to cause deenergization of the upper heater and energization of the lower heater when a predetermined part of the water in the tank has been heated to a predetermined temperature and to cause deenergization of the lower heater when substantially all of the water in the tank has been heated to a predetermined temperature.

7. A water heater control system for a hot water tank having an upper and a lower electric heater therefor, a single plural-contact three-position switch for selectively controlling said heaters, a pair of rods having different linear thermal expansion than said tank, the length of each rod

being slightly less than one-half of the length of the tank, extending longitudinally of the tank with the outer ends fixedly secured to the end portions of the tank, said rods jointly controlling said switch in accordance with the temperature of the water throughout the tank to cause energization of the upper heater only when the tank is full of cold water and to cause deenergization of the upper heater and energization of the lower heater when a predetermined part of the water in the tank has been heated to a predetermined temperature and to cause deenergization of the lower heater when substantially all of the water in the tank has been heated to a predetermined temperature and to cause reenergization of said lower heater in case of withdrawal of a predetermined relatively small amount of hot water from the tank.

8. A water heater control system for a hot water tank having an upper and a lower electric heater therefor, a single plural-contact three-position switch for selectively controlling said heaters, a pair of rods having different linear thermal expansion than said tank, the length of each rod being slightly less than one-half of the length of the tank, extending longitudinally of the tank with the outer ends fixedly secured to the end portions of the tank, said rods jointly controlling said switch in accordance with the temperature of the water throughout the tank to cause energization of the upper heater only when the tank is full of cold water and to cause deenergization of the upper heater and energization of the lower heater when a predetermined part of the water in the tank has been heated to a predetermined temperature and to cause deenergization of the lower heater when substantially all of the water in the tank has been heated to a predetermined temperature and to cause reenergization of said lower heater in case of withdrawal of a predetermined relatively large amount of hot water from the tank.

9. A water heater control system for a hot water tank having a cold water inlet at its lower end and a hot water outlet at its upper end and an upper and a lower electric heater, comprising a single plural-contact three-position switch for selectively controlling said heaters and means for actuating said switch comprising an upper rod having its upper end fixedly secured to the upper end of the tank, a lower rod having its lower end fixedly secured to the lower end of the tank, said rods extending longitudinally of said tank with their inner ends spaced apart, said rods having a linear thermal expansion different than that of the tank, means supporting said switch on the inner end of one of said rods and switch-actuating means engaged by the inner end of the other rod for causing movement of said switch into a position to effect energization of said upper heater only when the tank is substantially full of cold water.

10. A water heater control system for a hot water tank having a cold water inlet at its lower end and a hot water outlet at its upper end and an upper and a lower electric heater, comprising a single plural-contact three-position switch for selectively controlling said heaters and means for actuating said switch comprising an upper rod having its upper end fixedly secured to the upper end of the tank, a lower rod having its lower end fixedly secured to the lower end of the tank, said rods extending longitudinally of said tank with their inner ends spaced apart, said rods having a linear thermal expansion different than that

of the tank, means supporting said switch on the inner end of one of said rods and switch-actuating means engaged by the inner end of the other rod for causing movement of said switch into a position to effect energization of said upper heater only when the tank is substantially full of cold water and to cause deenergization of the upper heater and energization of the lower heater when a predetermined part of the water in the tank has been heated to a predetermined temperature.

11. A water heater control system for a hot water tank having a cold water inlet at its lower end and a hot water outlet at its upper end and an upper and a lower electric heater, comprising a single plural-contact three-position switch for selectively controlling said heaters and means for actuating said switch comprising an upper rod having its upper end fixedly secured to the upper end of the tank, a lower rod having its lower end fixedly secured to the lower end of the tank, said rods extending longitudinally of said tank with their inner ends spaced apart, said rods having a linear thermal expansion greater than that of the tank, means supporting said switch on the inner end of one of said rods and switch actuating means engaged by the inner end of the other rod for causing movement of said switch into a position to effect energization of said upper heater only when the tank is substantially full of cold water and to cause deenergization of the upper heater and energization of the lower heater when a predetermined part of the water in the tank has been heated to a predetermined temperature.

12. A water heater control system for a hot water tank having a cold water inlet at its lower end and a hot water outlet at its upper end and an upper and a lower electric heater, comprising a single plural-contact three-position switch for selectively controlling said heaters and means for

actuating said switch comprising an upper rod having its upper end fixedly secured to the upper end of the tank, a lower rod having its lower end fixedly secured to the lower end of the tank, said rods extending longitudinally of said tank with their inner ends spaced apart, said rods having a linear thermal expansion less than that of the tank, means supporting said switch on the inner end of one of said rods and switch-actuating means engaged by the inner end of the other rod for causing movement of said switch into a position to effect energization of said upper heater only when the tank is substantially full of cold water and to cause deenergization of the upper heater and energization of the lower heater when a predetermined part of the water in the tank has been heated to a predetermined temperature and to cause deenergization of the lower heater when substantially all of the water in the tank has been heated to a predetermined temperature and to cause reenergization of said lower heater in case of withdrawal of a predetermined relatively small amount of hot water from the tank.

13. A water heater control system for a hot water tank having a cold water inlet at its lower end and a hot water outlet at its upper end and an upper and a lower electric heater, comprising a single plural-contact three-position switch for selectively controlling said heaters and means for actuating said switch comprising an upper rod having its upper end fixedly secured to the upper end of the tank, a lower rod having its lower end fixedly secured to the lower end of the tank, said rods extending longitudinally of said tank with their inner ends spaced apart, said rods having a linear thermal expansion greater than that of the tank, means supporting said switch on the inner end of the lower of said rods and switch-actuating means engaged by the inner end of the upper rod for causing movement of said switch into a position to effect energization of said upper heater only when the tank is substantially full of cold water.

CLARK M. OSTERHELD.
